PIVOT MOUNTING FOR KNEELER RESTS OR
SIMILARLY MOUNTED ARTICLES

Robert C. Patterson, Grand Rapids, Mich., as-
signor to American Seating Company, Grand
Rapids, Mich., a corporation of New Jersey

Application February 3, 1947, Serial No. 726,066

2 Claims. (Cl. 155—166)

1

The present invention relates to pivot mountings for a kneeler rest or similarly mounted article, and more particularly to the type of kneeler rest which is pivotally mounted underneath and to the rear of a church pew for the use of occupants of the next pew to the rear; and other articles similarly mounted.

The primary objects of the invention are to provide a kneeler rest of the type above indicated which may be swung upwardly to a non-use position beneath the church pew on which it is mounted or may be swung downwardly to a use position extending rearwardly of said pew, in which latter position it may conveniently be knelt upon by the occupant of a pew to the rear of the pew on which the kneeler is mounted; to provide such a kneeler rest which is removably mounted and which may therefore be removed in order to facilitate such operations as varnishing the floor beneath the church pews or re-laying carpet thereunder, or for the purpose of re-upholstering the kneelers if they are of the upholstered type; to provide an improved pivot device for mounting a kneeler rest on a pew as above indicated or for removably mounting any element for swinging movement on a fixed supporting element; to provide such a pivot device which may readily and conveniently be installed on such swinging and fixed supporting element; and to provide such a device which is long-wearing in use and reasonably economical in manufacture.

An illustrative embodiment of the invention is shown in the accompanying drawings, wherein:

Figure 1 is a rear, perspective view of a church pew with a pair of kneeler rests secured thereto;

Figure 2 is a perspective view of a pintle member by means of which the kneeler rest is adapted for installation on the pew;

Figure 3 is a perspective view of a socket member by means of which the pew is adapted to support the kneeler rest;

Figure 4 is an enlarged, fragmentary sectional view of the kneeler rest and the adjacent pew support, the kneeler rest being here shown in a lowered use position;

Figure 5 is a fragmentary, sectional view of the same taken on line 5—5 of Figure 4;

Figure 6 is a fragmentary, sectional view taken on line 6—6 of Figure 5, the kneeler rest being on the near side of the plane of the section but being here indicated in an upwardly swung position in dotted lines; and

Figure 7 is a sectional view similar to Figure

6 and indicating the kneeler rest in a more rearwardly moved position than that indicated in Figure 6.

Referring now in detail to these drawings 5 wherein like parts are designated by the same numerals in the several views, the church pew shown in Figure 1 comprises a length of pewing 10 secured to and supported by a plurality of spaced, fixed, upright, supporting elements. As 10 shown these supporting elements comprise end supports 11, 12 of a decorative type, and a functional middle support 13. An element generally designated 14 adapted to serve as a kneeler rest extends between each of the pew end supports 11 and 12 and the middle support 13, these kneeler rests 14 being mounted for swinging movement to a raised position of non-use beneath the pew as indicated at the right of Figure 1 and to a lowered position of use extending 20 rearwardly of the pew as indicated at the left of Figure 1, in which latter position the kneeler rest may be knelt upon by an occupant of a pew disposed in the rear of the pew shown.

Each kneeler rest comprises a pair of spaced, 25 parallel arms 15, 16 connected by a horizontal kneeler bar 17 having its opposite ends secured by any suitable means such as wood screws (not shown) to the arms 15, 16 respectively. The kneeler bar 17 may desirably be upholstered as 30 by means of a sponge rubber pad 18 and an upholstery cover 19 disposed over the pad 18 and secured to the opposite or under surface of the kneeler bar by any suitable means such as tacks (not shown).

The spaced, upright supports upon which each kneeler rest is mounted are provided with socket members 20 having screw-receiving apertures 21 and secured as by wood screws 22 near the lower, rearward, inner corners of said supports and 40 with the laterally inwardly extending cylindrical sockets 23 thereof in horizontal, axial alignment. A gate 24 extends horizontally rearwardly through the surrounding wall 25 of each socket 23, said gates being of slightly less height 45 than the diameter of the sockets 23. It will be seen that the socket members 20 may be identically formed thus reducing the cost of their manufacture, and the socket members on the supporting elements to the left are installed in 50 an inverted position relative to those on the supporting elements to the right.

Pintle members 26 are provided for the opposite ends of the kneeler rest 14, and these may likewise be of identical formation thus obviating the expense of manufacturing these pintle mem-

bers in "rights" and "lefts." Each pintle member 26 has a pair of oppositely laterally extending pintles 27 of cylindrical segmental formation, and a screw-receiving aperture 28 located eccentrically of the pintles 27 and having countersinks on both sides of the pintle member 26. A pintle member 26 is installed on the outer side of each of the arms 15, 16 of the kneeler rest, one of the pintles 27 of each member 26 being snugly fitted into a bore or recess 29 in the adjacent arm 15 or 16, and the other pintle 27 extending outwardly for turnable engagement in the adjacent socket 23. A wood-screw 30 passing through the aperture 28 secures each pintle member 26 to the adjacent arm 15 or 16.

In the normal use of the structure, the kneeler rest is freely turnable to its raised or lowered positions, the outwardly extending pintles 27 being freely turnable in the sockets 23 and being retained therein because the greater diameter of each pintle is larger than the height of the adjacent gate 24. When the kneeler rest 14 is in its lowered position of use shown in Figure 4, the chordal surface 31 of each pintle is inclined rearwardly-downwardly at an angle of approximately 60 degrees from horizontal. However, when the kneeler rest 14 is turned from its position shown in Figure 4 to the partially raised position indicated in Figure 6, said chordal surfaces 31 are turned to a horizontal position with the segmental void 32 of each pintle uppermost. A slight lifting of the kneeler rest from its position shown in Figure 6 brings the smaller diameter of each outwardly extending pintle 27 into registry with the gate 24 of the adjacent socket member and the pintles 27 are thus free to be withdrawn from the sockets indicated in Figure 7. The kneeler rest may thus be removed from its mountings, and may be replaced therein in a reverse manner.

Rubber bumpers 33 may be installed on the rearward edges of the arms 15, 16 of the kneeler rests in order to silence their movements to lowered positions. Similar rubber bumpers 34 may be installed on the forward edges of said arms in order to silence the kneeler rests' movements to raised positions.

As shown in the drawings, and particularly in Figure 5, the pintles 27 of the pintle members 26 are slightly tapered outwardly in order to facilitate their removal from the molds when cast.

It will be seen that the invention provides an improved pivot device for mounting kneeler rests on pew supports, wherein there are no objectionable metal-to-wood wearing surfaces, and wherein the several parts of the pivot device may be inexpensively assembled to the kneeler rests and pew supports at the factory and the kneeler rests thereafter installed on the pews; and while but one specific embodiment of the invention has been herein shown and described, it will be understood that numerous details may be altered or omitted without departing from the spirit of the invention as the same is defined by the following claims:

I claim:

1. In a structure of the class described: spaced upright pew supports; a kneeler rest extending between said pew supports and comprising a horizontal kneeler bar and parallel arms extending laterally from the opposite ends of said kneeler bar adjacent the pew supports respectively; socket members secured to the pew supports and extending mutually inwardly therefrom, said members having horizontally aligned substantially cylindrical sockets therein and having gates

extending horizontally rearwardly from the sockets through the walls of the socket members, said gates being of lesser vertical dimension than the diameter of the sockets; pintle members secured to the parallel arms respectively of the kneeler rest and having axially aligned, outwardly extending pintles thereon, said pintles being of substantially cylindrical segmental formation and being receivable through the gates of the socket members into turnable disposition within the sockets thereof whereby the kneeler rest is supported swingably about a horizontal axis to a lowered position for kneeling and to a raised position of non-use; the cylindrical segmental pintles being so disposed on the parallel arms of the kneeler rest as to present their smallest dimension to and thus be receivable and removable through said gates when the kneeler rest is in a swung position intermediate its raised and lowered positions.

2. In a structure of the class described: spaced upright pew supports; a kneeler rest extending between said pew supports and comprising a horizontal kneeler bar and parallel arms extending laterally from the opposite ends of said kneeler bar adjacent the pew supports respectively; socket members secured to the pew supports and extending mutually inwardly therefrom, said members having horizontally aligned substantially cylindrical sockets therein and having gates extending horizontally rearwardly from the sockets through the walls of the socket members, said gates being of lesser vertical dimension than the diameter of the sockets and the bottoms of the gates being at a higher level than the bottoms of the sockets; pintle members secured to the parallel arms respectively of the kneeler rest and having axially aligned, outwardly extending pintles thereon, said pintles being of substantially cylindrical segmental formation and being receivable through the gates of the socket members into turnable disposition within the sockets thereof whereby the kneeler rest is supported swingably about a horizontal axis to a lowered position for kneeling and to a raised position of non-use; the cylindrical segmental pintles being so disposed on the parallel arms of the kneeler rest as to present their smallest dimension to and thus be receivable and removable through said gates when the kneeler rest is in a swung position intermediate its raised and lowered positions and in a slightly vertically lifted position.

ROBERT C. PATTERSON.
